UNITED STATES PATENT OFFICE

106,393

DESIGN FOR A DRESS

Mercedes Hall, New York, N. Y.

Application July 31, 1937, Serial No. 70,761

Term of patent 3½ years

To all whom it may concern:

Be it known that I, Mercedes Hall, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the specific arrangement of the button trim on the waist and shoulder-strap portions, as shown.

I claim:

The ornamental design for a dress, substantially as shown, and described.

MERCEDES HALL.
